(57) **CLAIM**

The ornamental design for a printer for printing three-dimensional objects, as shown and described.

DESCRIPTION

FIG. 1 is an isometric view of the printer;

FIG. 2 is a left side view of the printer;

FIG. 3 is a right side view of the printer;

FIG. 4 is a bottom view of the printer; and,

FIG. 5 is a back view of the printer.

The broken-line disclosure represents portions of the printer, which form no part of the claimed design.

1 Claim, 5 Drawing Sheets
